US00D842449S

(12) **United States Design Patent** (10) Patent No.: **US D842,449 S**
Chang et al. (45) Date of Patent: ** Mar. 5, 2019

(54) **GRILLE**

(71) Applicant: **Broan-NuTone LLC**, Hartford, WI (US)
(72) Inventors: **Hyuk-Jae Chang**, Pittsburgh, PA (US); **Benjamin Thorpe Puffer**, Hartford, WI (US); **Michael Patton**, St. Joseph, WI (US)

(73) Assignee: **Broan-NuTone LLC**, Hartford, WI (US)

(**) Term: **15 Years**

(21) Appl. No.: **29/584,141**

(22) Filed: **Nov. 11, 2016**

(51) LOC (11) Cl. **23-04**

(52) U.S. Cl.

USPC **D23/412**; D23/385; D23/371

(58) **Field of Classification Search**

USPC D23/370, 371, 377-379, 381, 382, D23/385-388, 411, 412; D26/59
CPC F04D 25/088; F04D 29/005; F04D 29/601; F04D 29/324; F21V 33/0096; F21V 33/0092; F24F 13/078
